FUEL MIXING DEVICE

Willard J. Dunston, Watertown, Mass., assignor
of one-half to Cleveland A. Ballou, Newton
Center, Mass.

Application October 21, 1937, Serial No. 170,239

5 Claims. (Cl. 48—180)

This invention relates to devices for mixing liquid fuels and air in producing a highly efficient combustible or explosive vapor mixture. The invention consists in a novel device for 5 breaking up and finely dividing or vaporizing the small globules of liquid fuel found in the fuel mixture after the usual carburizing has taken place. By using the device of my invention, it is possible to obtain from a given amount of liquid fuel more energy than has been obtainable heretofore under commercial conditions. An important field of use of the invention lies in internal combustion engines used in automobiles although it may be advantageously applied to any 10 internal combustion engine or to any system where high efficiency of fuel is a desirable object.

The basis of my invention is the discovery that by forcing the entire carburized air-gas current to follow a circuitous or undulatory path and simultaneously admitting air jets into that current a more perfect vaporizing or mixing effect is achieved than has been heretofore known. To this end an important feature of my invention 20 consists in a plurality of banks or a nest of slender perforated tubes arranged to traverse the duct leading from the carburetor to the combustion space of the engine, or formed in the carburetor, the tubes being perforated to admit air jets of controlled volume into the current of air-gas mixture flowing in the duct.

Many attempts have been made to increase the efficiency of liquid fuel mixtures but none has found favor, chiefly because the problems involved have not been clearly appreciated, and because no adequate control means have been provided.

For example, tubes have been heretofore introduced into the air-gas duct, but not in such 40 a manner as efficiently to affect the gaseous mixture flowing therein or as to prevent coalescence of liquid particles after the tubes have once been passed. As distinguished from prior attempts, the present invention contemplates the employment 45 of banks of tubes so arranged as to fill substantially the entire air-gas duct and cause the whole flow or current to undulate sharply in passing through them. Further, the tubes are effective not merely in a single transverse plane but 50 throughout a substantial length of the duct thus insuring a stable condition of vaporization in the treated mixture.

Another condition which is provided for in the present invention is the practical necessity of enriching the treated mixture while the engine is

running at low or at very high speeds as compared to its composition while the engine is running at intermediate speeds. This condition is met in accordance with the present invention by connections with the throttle valve which permits, increasingly and decreasingly, the admission of air through the transverse tubes of the device in volume corresponding to the range of engine speed. When the throttle is fully closed the air supply to the tubes is cut off and begins 10 to be admitted only as the throttle is opened in bringing the engine up to speed. Again, as the throttle approaches its wide-open position the air supply is progressively reduced.

These and other features and advantages of my invention will be more readily understood and appreciated from the following description of a preferred embodiment thereof selected for purposes of illustration and shown in the accompanying drawings, in which,

Fig. 1 is a view in front elevation of a device embodying my invention,

Fig. 2 is a view of the device in end elevation.

Fig. 3 is a corresponding plan view,

Fig. 4 is a view in cross section taken on the line IV—IV of Fig. 1, and

Fig. 5 is a view in cross section taken on the line V—V of Fig. 3.

In order to suggest the approximate position of my device as usually installed I have shown 30 in Fig. 2 a portion of a conventional carburetor. A pipe or duct 11, having a lower attaching flange 10 extends vertically up from the carburetor and has within it a butterfly valve 49 carried by a transverse shaft 13 controlled by the throttle lever 14 on the outer end of the shaft. The gasoline, or other liquid fuel, is drawn upwardly as a vapor from the carburetor into the vertical duct 11 on its way to the engine. The pipe forming the duct 11 is provided with an upper flange 15 40 on which rests a flat rectangular block 16 of bronze or suitable material. Above the block 16 is a fitting 18 shaped as a continuation of the duct and this has a flange 17 resting on the block 16, the flanges 15 and 17 and the block 16 between them being securely held together by vertical bolts 19.

The block 16 has a circular passage corresponding to the inside diameter of the duct 11 and the fitting 18 above it. In this passage of 50 the block 16 is mounted a nest of slender transverse tubes 32, herein shown as arranged in three parallel banks, one above another or one behind another relative to the flow of vapor in the duct. One desirable pattern or arrangement of the 55

tubes includes an upper bank of four tubes, an intermediate bank of five tubes and a lower bank of four tubes. As best shown in Fig. 5, the tubes of each bank are arranged in staggered and 5 overlapping relation to the tubes of the next bank so that the upwardly flowing vapor stream is caused to undulate laterally in an abrupt manner. It will be noted that the pattern of tubes is such as to fill the entire duct and consequently 10 the whole current is acted upon and none of it escapes the back-and-forth deflecting action of the tubes 32.

Each of the tubes 32 is provided with a series 15 of air jet openings 33, these being arranged in rows in the upper and in both side walls of the tubes, leaving imperforate the sides of the tubes which face the oncoming vapor stream. The tubes 32 are sealed at their inner ends in the body of the block 16 and at their opposite ends they open 20 into a transverse air passage 27. Air is admitted to the passage 27 through a pipe or duct 20 which may be provided with any conventional strainer, not herein shown. In assembling the tubes 32 in the block 16 bores are drilled into the 25 block and intersect the air passage 27. The outer ends 30 of these bores are permanently closed by a cover plate 31 seen in Figs. 3 and 4.

The flow of air through the air passage 27 is controlled by two separate valves, one under the immediate control of the operator and the other 30 operated by connection with the throttle. The first of these valves is a sleeve valve 21 rotatably mounted in the passage 27 opposite the end of the air duct 20. It is provided with an operating arm 22 which is connected by a rod 26 to the instrument board of the automobile within convenient reach of the operator. A collar 23 having a slotted segment 24 is adjustable about the flanged end of the valve 21, being held in position 35 by a screw 25. The segment provides stop faces for limiting the throw of the arm 22 and causing the valve 21 either to register with the air duct 20 or to close it.

The sleeve valve 21 is not used unless the operator desires to cut out entirely the admission of 45 air to the fuel mixture through the medium of the perforated tubes 32. In very cold weather this may be temporarily desirable and consequently the operator may close the valve 21.

The second of the two valves is a butterfly valve 50 28 located within the air passage 27 and carried on a shaft 35 rotatable in a bore in the block 16. A set screw 29 forms an abutment for the valve 28 when the latter is open. A collar 36 is keyed on 55 the end of the shaft 35 and is recessed at substantially opposite points in its circumference. A grooved stud 37 is eccentrically mounted on the outer end of the collar 36 and around the stud is caught one end of a helical tension spring 38. The other end of the spring 38 is fastened to a 60 stud 39 set in the block 16 and serving as a pivot pin on which are mounted an L-shaped pawl 40, a straight pick 44 and a wedge shaped plate 43. The pawl 40 has a downwardly extending slotted arm 41 through which passes a clamping screw 42 which is threaded into the plate 43. The pick 44 has an upwardly extending slotted arm 45 with a clamping screw 46 which is also threaded into the plate 43. An S-shaped rod 47 is pivotally connected at one end to the plate 43 and at its other end it is connected by a pin 48 to an ear 50 projecting from the throttle lever 14.

Accordingly, when the throttle lever is swung in a counter-clockwise direction as seen in Fig. 1 by the depression of the accelerator and the throt-

tle valve 49 begins to open, the plate 43 is also swung upwardly by the rod 47 carrying both the pawl 40 and the pick 44 with it. The pawl 40 acts first to rotate the collar 36 and open the air valve 28 against the tension of the spring 38. 5 The point in the opening movement of the throttle valve at which the pawl begins to act may be adjustably determined by regulating the position thereof on the carrying plate 43 through the medium of the adjusting screw 42. 10

The pawl 40 continues to open the air valve 28 as the throttle valve is opened and up to a point corresponding to moderate driving speed and in this motion the spring 38 is carried across the axis of the disk 36. If the throttle valve is still further opened and the engine reaches a high speed the pick 44 comes into action, engaging the recess in the collar diametrically opposite to that engaged by the pawl 40 and turning the collar 36 reversely progressively to close the valve 28 20 and gradually shut off the air supply to the tubes 32. It will be noted that both the pawl 40 and the pick 44 pass out of operative engagement with the collar 36 when their respective functions have been carried out. When the throttle 25 valve is allowed to close all parts reassume their initial position as represented in Fig. 1. The effective path of the pick 44 may be adjusted by regulating its position on the carrying plate 43 through the medium of the adjusting screw 46. 30

It will thus be seen that I have provided the nest of perforated tubes 33 in a position to impart an undulating movement to the entire air-gas mixture and at the same time break up this mixture and all drops of liquid fuel therein, by 35 the admission of air in a widely distributed area. Thus is produced a homogeneous vaporized mixture in the form of the finest mist, resulting in (1) most important and substantial economy of raw fuel (gasoline) and (2) valuable increase in 40 efficiency of operation of the motor.

In the installation selected to illustrate my invention the air-gas mixture passes upwardly from the carburetor to the intake manifold of the engine, but it will be understood that my invention 45 may be equally well applied to an installation in which the air-gas mixture passes downwardly to the engine. In fact the direction of flow of the mixture has no effect on the beneficial result I am able to achieve.

Further, while I have shown the tubes 32 and the valves 21 and 28 as mounted as a unit in a removable block it will be understood that it would be within the scope of the invention to build these elements directly into the carburetor 55 structure.

Having thus described my invention what I claim as new and desire to secure by Letters Patent is—

1. In a fuel mixing device comprising a duct, 60 a throttle valve in said duct, a plurality of banks of perforated tubes traversing said duct, and an air conduit connected to said tubes; a butterfly valve in said air conduit, a shaft controlling said valve, a carrier plate pivotally mounted on said duct, a pick and a pawl pivotally secured to said plate, an S-shaped connecting rod carried by said throttle valve connected to said plate, and a spring connecting said carrier plate and butterfly valve, whereby partial opening of said 65 throttle valve causes said pawl to open said butterfly valve, and further opening of said throttle valve causes said pick to close said butterfly valve.

2. In a fuel mixing device having an air-gas duct provided with a throttle valve, tubes for ad- 75

mitting air to the duct beyond the throttle valve, an air valve, and a carrier plate movable simultaneously with the throttle valve; a pawl adjustably mounted on the carrier plate and arranged 5 to open and then to release the air valve in the continuous movement of the carrier plate.

3. In a fuel mixing device having an air-gas duct provided with a throttle valve, means for admitting a controlled amount of air to the duct 10 beyond the throttle valve including an air valve, and a carrier plate movable simultaneously with the throttle valve; adjustable means operated by the carrier plate and arranged to close and then release the air valve in the continuous movement 15 of the carrier plate.

4. In a fuel mixing device having an air-gas duct provided with a throttle valve and a carrier plate movable therewith, a plurality of transverse perforated tubes for admitting air to the 20 air gas stream beyond the throttle valve, and an air valve for regulating the supply of air to said tubes; a pick adjustably mounted on said car-

rier plate and arranged to engage said air valve, a pawl also mounted on said carrier plate, and a tension spring connecting said valve and said carrier plate, whereby during the continued opening of the throttle valve the carrier plate 5 and the pick and pawl operate first to open and then to close the air valve against the tension of said spring.

5. In a fuel mixing device having an air-gas duct provided with a throttle valve, means including a plurality of perforated transverse tubes and an air valve for admitting a controlled amount of air to the duct beyond the throttle valve, a carrier plate movable simultaneously with the throttle valve, means secured to the 10 carrier plate and arranged progressively to open the air valve when the throttle valve is being opened, and other means secured to the carrier plate for thereafter closing the air valve as the 15 throttle valve is being still further opened. 20

WILLARD J. DUNSTON.
